UNITED STATES PATENT OFFICE.

SECONDO L. CASELLA, OF NEW YORK, N. Y., ASSIGNOR TO YALE ELECTRIC CORPORATION, OF BROOKLYN, NEW YORK, A CORPORATION OF NEW YORK.

BOBBIN TRIMMING AND CLEANING MACHINE.

Application filed August 6, 1927. Serial No. 211,106.

This invention relates to a machine for trimming the relatively sharp corner or edge from battery bobbins of the type employed in flashlight and other dry battery cells, where-
5 in the bobbin includes a carbon electrode about which the depolarizing mixture is molded in powdered form.

Bobbins of the above type are extremely fragile and must be handled with particular care when used naked, that is without a wrapper or other cover for the depolarizing mixture, otherwise careless handling of the bobbins during the manufacture of battery cells is likely to cause particles of depolarizing
10 mixture particularly at the sharp corner or edge of the bobbin to be broken away, with the result that such particles cause internal short-circuiting of the cells, thus rendering them useless after a relatively short period
20 of time.

An object of the present invention is to provide a simple and efficient machine for trimming from bobbins of the above type the sharp corner or edge of the depolarizing mixture, thus rendering such bobbins less likely to disintegrate during assembling of the battery cell.

A further object of the invention is to provide in a machine of the character mentioned, means for removing from the surface of the bobbin such loose and finely divided particles of depolarizing material as may be thereon before and after the trimming operation.

35 Other objects and advantages of the invention will become apparent from the following description, taken in connection with the accompanying drawings in which—

Figure 1 is a plan view of the machine.
40 Figure 2 is a front view of the machine as viewed from the right in Figure 1. Figure 3 is a vertical sectional view taken on the line 3—3 of Figure 1, Figure 4 is a detail view showing means by which the cutting tool for trimming the bobbin is mounted, and Figure 5 is a perspective view of a bobbin from which the relatively sharp corner or edge has been removed by the machine shown in Figures 1 to 4 inclusive.

50 Referring to the drawing the numeral 10 indicates a base or support upon which is suitably mounted an electric motor 11, to the shaft of which is connected a sleeve 12, provided with a vertically disposed disc 13.

55 The disc 13 is provided with a support 14

having an inclined face 15, which is undercut as shown at 16 to receive the beveled margin of a cutter 17. This cutter 17 is removably held in position upon the support 14 by a clamp plate 19 having one edge undercut, as 60 shown at 20, to receive the beveled margin of the cutter 17. The holding plate 19 is suitably connected to the support 14 by a pair of lag screws 22 which may be partially removed to permit the cutter 17 to be removed for 65 sharpening or to permit such cutter to be adjusted horizontally, as viewed in Figure 3, whereby the amount of material to be removed from the corner or edge of the bobbin may be varied.

70 When presenting the bobbin to the cutter 17, such bobbin is projected through an annular tube 24 until the bottom of the carbon electrode engages a stop lug 25 carried by the disc 13 centrally thereof. This annular tube 75 24 serves as an air duct adapted to communicate, through a conduit 18, with a suitable source of air pressure, not shown, and is provided with a series of perforations 26, which are so disposed as to project a plurality of 80 streams of air towards the disc 13 and towards the axis about which such disc rotates at such an angle that the streams of air impinge upon the peripheral surface of the bobbin and remove therefrom, both before and after 85 the trimming operation, such loose or segregated particles of depolarizing mixture as may adhere thereto.

85 In front of the annular duct 24, which is supported coaxially with the disc 13 by a 90 suitable bracket 27 carried by the base 10, is arranged a supporting block 28 upon which is positioned a bobbin guide or rest 29. This bobbin guide is formed with a pair of in- 95 wardly and downwardly converging faces 30 which are so spaced from each other and from the axis of the disc 13 that when the bobbin is at rest thereon such bobbin may be maintained in alignment with the axis of the disc 13 with the lower end of 100 the carbon electrode 31 resting against the stop lug 25, thereby insuring uniform trimming of the bobbin to produce at the lower end of each a beveled face 32 as shown in Figure 5.

105 Between the bobbin guide 29 and the cutter 17 is arranged a guard plate 33 which is suitably connected to the supporting block 28 and provided with a central opening 34 through which the bobbin is projected as 110

it is presented to the cutter 17. This guard plate 33 serves to insure the operator's hand against injury by the rotating cutter 17 and also serves to prevent such particles of depolarizing material as are removed by the cutter 17 from being unduly disturbed by the force of the streams of air issuing from the perforations 26 formed in the annular tube 24.

10. What is claimed is:

1. A battery bobbin trimming machine including a rotary cutter adapted to engage a corner of a bobbin and remove a portion of the depolarizing material from the bobbin in 15 that vicinity, a support for supporting the bobbin as it is presented to said cutter, and fluid pressure means for removing loose particles of depolarizing material from the surface of the bobbin, said fluid pressure means 20 including an annular perforated tube through which the bobbins are passed as they are presented to said cutter and through which the bobbins are withdrawn as they are retracted from said cutter.

25. 2. A battery bobbin trimming machine including a rotary disc, a cutter carried by said disc and having its cutting edge in-

clined with respect to the axis of said disc, and a guiding support adapted to support the bobbin as it is presented to said cutter, 30 and an annular perforated tube adapted for connection with a source of air pressure, said tube being so located with respect to said support as to encircle the bobbin as it is presented to and retracted from said cutter and having its perforations so arranged as to direct their respective jets of air onto the surface of the bobbin as it is presented to and retracted from said cutter.

3. A battery bobbin trimming machine including a rotary cutter adapted to engage a corner of a bobbin and remove a portion of the depolarizing material from the bobbin in that vicinity, a fluid pressure means arranged adjacent said cutter and having a plurality of air ports adapted to deliver a plurality of jets of air towards the axis of rotation of said cutter and into contact with the surface of the bobbin as it is retracted from said cutter. 45

50 In testimony whereof, I have affixed my signature to this specification.

SECONDO L. CASELLA.
